UNITED STATES PATENT OFFICE

2,031,338

WINDOW SASH

Louis Stoltenberg, Oakland, Calif.

Application October 29, 1934, Serial No. 750,484

1 Claim. (Cl. 20—68)

This invention has reference to new and useful improvements in weather proofing and weather stripping also the rattle proofing of double hung windows.

5 The primary object of the invention is the provision of means for weather stripping and weather proofing double hung windows which consists of applying to the upper and lower sashes of a double hung window casement spring controlled weather strips adapted to bear against the outer surfaces of both the upper and lower sashes thereof to render said sashes weather proof, anti-rattling proof, and substantially burglar proof.

10 A further object of the invention is to provide means for guiding and weather proofing upper and lower sashes in such manner that the same are rendered anti-rattling and at the same time rendering the sashes easily movable in the casement as the spring controlled strips prevent binding therein due to warping of the sashes due to weather conditions.

15 A still further object of the invention is the provision of means comprising spring actuated weather strips adapted to bear at all times against both upper and lower sashes of a double hung window and in which the spring urging means is completely concealed from view.

20 An additional object of the invention is that the device may be readily and easily applied or installed to any double hung window of the usual type.

25 Additional to the foregoing objects is that of providing a device of the class indicated that is simple in construction and design and that is positive in its action and that may be cheaply manufactured and installed on any double hung window casement by a layman.

30 Other objects and advantages of the invention will become apparent with reference to the subjoined specification and the accompanying one sheet of drawings in which:—

35 Figure 1 represents a double hung window and casement looking from the inside of a structure and showing my improved weather stripping as applied to the upper and lower sashes of a double hung window casement;

40 Figure 2 is an enlarged sectional detail view taken through both upper and lower sashes and showing my improved weather stripping applied thereto;

45 Figure 3 is a transverse section taken on the line 3—3 of Figure 2 and showing one side of the casement and illustrating the spring pressed strips for both upper and lower sashes of the casement;

50 Figure 4 is an enlarged fragmentary face view

of one of the weather strips for the lower sash and illustrating the spring means for urging said strips against said window sash;

5 Figure 5 is an enlarged fragmentary face view of one of the strips for the upper sash of the window and showing the slightly modified spring means for urging this sash toward the dividing strip of casement; and

Figure 6 is a face view partially in section illustrating the slotted guide means for the outer strip 10 of the casement.

Referring now more particularly to Figures 1 and 2 it will be observed that my improved weather stripping device consists of the usual casement 8 having lower and upper sliding and 15 counterbalanced sashes 9 and 10, respectively, of the usual type said sashes being slidable in the casement along the usual guiding strip 11.

The lower or inner sash 9 is provided with spring pressed weather and anti-rattle proofing 20 strips 12 and 13 and the upper or outer sash 10 is provided with similar strips 14.

Referring now to Figures 2, 3 and 4 the inner strips 12 and 13 bear against the sash 9 and the strips 14 bear against the sash 10, one of the 25 strips 12 being shown in detail in Figure 4 and showing slots 15 through which 16 extend and having at their upper and lower ends spring elements 17 operating against fixed pins or screws 18 so that said strips are always normally urged 30 against the inner face of the sash 9.

The strips 14 for the outer or upper sash 10 are arranged slightly different than the strips 12 and 13 in that the screws 19 are counter-sunk in apertures 20 slotted as indicated at 21, Figures 3 and 6. In Figure 5 the spring elements 22 bearing against the pins or screws 23 illustrate the means for urging these strips against the inner face of the vertically grooved sash 10, as clearly shown in Figure 3.

40 It is obvious that the heads of the screws 19 of the strips 14 must be countersunk or placed in the apertures 20 so that these heads will not contact the sliding sash 10 while in the sash 9 the strips 12 and 13 are arranged on the outside 45 face thereof as shown.

It will thus be observed that I have produced weather stripping for double hung windows that places frictional tension against both lower and upper sashes 9 and 10 respectively, and that said 50 tension of the strips forces the same inwardly against the dividing strip 11 and toward each other thereby preventing rattling of both sashes and at the same time preventing cold drafts from entering the inside of a structure so equipped 55

and, furthermore, allows the sashes to be moved easily up or down in the casement.

I claim and desire to secure by Letters Patent of the United States the following:—

- 5 In a device of the class described, weather stripping for windows, said weather stripping having transversely arranged guide slots formed therein, pins extending through said slots, addi-

tional slots formed in said strips, flat springs mounted in said strips and extending into said last mentioned slots, and fixed counter-sunk headed pins extending from the window casement and engaging said springs whereby said strips are urged tightly against the window sashes.

LOUIS STOLTENBERG.
